UNITED STATES PATENT OFFICE.

RICHARD H. RICE, OF LYNN, MASSACHUSETTS, ASSIGNOR TO GENERAL ELECTRIC COMPANY, A CORPORATION OF NEW YORK.

ELASTIC-FLUID TURBINE.

1,325,208.

Specification of Letters Patent. Patented Dec. 16, 1919.

Application filed November 19, 1917. Serial No. 202,688.

To all whom it may concern:

Be it known that I, RICHARD H. RICE, a citizen of the United States, residing at Lynn, county of Essex, State of Massachusetts, have invented certain new and useful Improvements in Elastic-Fluid Turbines, of which the following is a specification.

The present invention relates to elastic fluid turbines, and particularly to turbines of the type comprising a plurality of disks or wheels mounted on a shaft and carrying suitable buckets upon the periphery. With such turbines it is important that the disks or wheels be made as light as possible in order to reduce the weight of the machine thereby reducing its size, and also the cost of manufacture. In addition, by making the wheels or disks as thin as possible, particularly at the hubs, the distance between bearings may be reduced, or a larger number of stages may be put in in the same space.

A desirable form of turbine wheel, due to its cheapness to manufacture, is one pressed up from sheet material, but, so far as I am aware, up to the present time no practical commercial wheel of this type has been made, at least for turbines of substantial size. This has been due primarily to the fact that there was not sufficient material in the hub of the wheel to firmly anchor it to the shaft so that it would withstand the stresses set up due to centrifugal action, and to the temperature changes which are continually going on in the turbine due to fluctuation in load and variations in the vacuum. As is obvious, the wheels will respond much more quickly to temperature changes than will the heavy shaft, and as a consequence there is very unequal expansion of the wheels and shaft, and if the wheels are rigidly connected to the shaft stresses of a substantial value are set up in the hubs. If the hubs are made too light these stresses may cause the wheels to distort and possibly loosen on the shaft.

The object of my invention is to provide an improved wheel structure which will permit of expansion due to temperature changes without causing the wheel to distort or loosen on the shaft or, in other words, to provide a wheel in which stresses in the hub, due to unequal expansion, will be to a great extent eliminated.

For a consideration of what I believe to be novel and my invention, attention is directed to the accompanying specification and the claims appended thereto.

In the drawing, the figure is a sectional view through a turbine wheel embodying my invention.

In carrying out my invention, I provide the turbine wheel adjacent the hub with an annular offset which serves as a yielding connection between the wheel and the hub to permit the wheel to expand due to temperature changes independently of the hub so as to relieve the stresses which would otherwise be set up in the hub. Due to this arrangement I am enabled to construct a turbine wheel by pressing it up from sheet material.

Referring to the drawing, a turbine wheel is shown comprising two plates 5 and 6, each provided with an offset 7 which preferably extends at about right angles to the plane of the plates. This means, in substance, that each plate comprises an inner portion and an outer portion with a yielding connection between them, the yielding connection being the offset portion of the wheel. The hub of the wheel is formed by providing the plates at their central opening with flanges 8 over which are forced rings 9 which are riveted in place, as indicated at 10. These rings 9 may be forced into place with a sufficiently tight fit to slightly distort the flanges 8, and after being riveted into place the central opening of the wheel 90 may be bored out to proper dimensions. The plates 5 and 6 are held in spaced relation at their peripheries by spacing members 11 to which the plates are riveted, as indicated at 12. 13 indicates the turbine buckets which may be fastened to the wheel in any suitable manner, and 14 indicates a shaft on which the wheel is mounted.

The structure has the advantage that it is cheap to manufacture, light in weight, and at the same time sufficiently strong and rigid to withstand all stresses set up in it due to centrifugal force, and unequal expansion. This is in a great measure due to the fact that the stresses set up in the hub by unequal expansion will not be large due to the offsets in the plates permitting the wheel to expand independently of the hub to such an extent as to relieve the hub of such stresses.

- In accordance with the provisions of the patent statutes, I have described the principle of operation of my invention, together with the apparatus which I now consider 5 to represent the best embodiment thereof; but I desire to have it understood that the apparatus shown is only illustrative and that the invention can be carried out by other means.
- 10 10 What I claim as new and desire to secure by Letters Patent of the United States, is:
1. A turbine wheel comprising two plates fastened together at their central parts to form a hub portion, buckets carried by the 15 rims of said plates, said plates each having annular offsets adjacent the hub portion to form a yielding connection whereby the radially outer portion of the wheel may expand substantially independently of the hub.
  2. A turbine wheel comprising a plate having a flange at its center and a ring 20 pressed over the flange to form a wheel hub, said plate having an annular offset ad-

acent the hub to permit the radially outer portion of the wheel to expand substantially independently of the hub. 25

3. A turbine wheel pressed up from sheet material, comprising two plates, each provided with an offset adjacent the hub, said plates being arranged with the offsets facing in opposite directions and toward each other, and means fastening said plates together whereby the radially outer portion of the wheel may expand substantially independently of the hub. 30

35 4. A turbine wheel pressed up from sheet material, comprising two plates having outwarded flanges at their centers and rings pressed over them to form hubs, each of said plates being formed with an annular offset adjacent the hub, and buckets carried by said plates.

In witness whereof, I have hereunto set my hand this 13th day of November, 1917.

RICHARD H. RICE.
